UNITED STATES PATENT OFFICE.

WILLIAM A. RINGLER, OF PHILADELPHIA, PENNSYLVANIA, ASSIGNOR TO GLOBE
WERNICKE CO., OF CINCINNATI, OHIO, A CORPORATION OF OHIO.

VERTICAL FILING SYSTEM.

Application filed April 15, 1921. Serial No. 461,723.

To all whom it may concern:

Be it known that I, WILLIAM A. RINGLER, a citizen of the United States, residing in the city and county of Philadelphia, State 5 of Pennsylvania, have invented a new and useful Vertical Filing System, of which the following is a specification.

My present invention comprehends a novel construction and arrangement of a visible 10 filing system wherein the filing units are filed vertically and when they are raised each filing unit opens out laterally so as to assume substantially a horizontal position and the upper faces of the cards are readily 15 accessible to the operator.

It further comprehends a novel construction and arrangement of a filing unit and a 20 novel construction of a housing or cabinet to receive the unit which latter may be employed either with or without a follower block as desired.

It further comprehends a novel construction of a filing unit wherein a guide member is employed to which the frame is mov- 25 ably connected and adapted to detachably carry the various cards and their adjuncts.

Other novel features of construction and 30 advantage will hereinafter more clearly appear in the detailed description.

For the purpose of illustrating my invention, I have shown in the accompanying drawings embodiments thereof which are at present preferred by me, since these embodiments will be found in practice to give satis- 35 factory and reliable results, although it is to be understood that the various instrumentalities of which my invention consists can be variously arranged and organized and that my invention is not limited to the precise 40 arrangement and organization of these instrumentalities as herein shown and described.

Figure 1 represents, in perspective, a vertical filing system, embodying my invention, 45 one of the filing units being shown as partially withdrawn from the cabinet.

Figure 2 represents a perspective view 50 similar to Figure 1 showing one of the filing units as having been raised sufficiently to permit the card-carrying frame to be presented substantially horizontally above the cabinet.

Figure 3 represents, in front elevation, a guide plate.

Figure 4 represents, in front elevation, a 55 card-carrying frame.

Figure 5 represents a section on line 5—5 of Figure 2 with the frames in closed position.

Figure 6 represents a section on line 6—6 60 of Figure 1.

Figure 7 represents, in perspective, an- 65 other embodiment of my invention with the filing units in their closed position.

Figure 8 represents a perspective view 65 similar to Figure 7 but showing one of the filing units in its open position.

Figure 9 represents a section on line 9—9 of Figure 8.

Figure 10 represents a section on line 10— 70 10 of Figure 7.

Figure 11 represents a section on line 11— 11 of Figure 8.

Figure 12 represents, in perspective, the 75 filing unit guide member in detached position.

Figure 13 represents, in perspective and in detached position, a filing unit with the card carrying frame in its open position.

Figure 14 represents a section on line 14— 80 14 of Figure 12.

Figure 15 represents a top plan view of 85 the card-carrying frame of the filing unit in detached position.

Figure 16 represents a top plan view of 90 another embodiment of a card-carrying frame which is employed in conjunction with the embodiment seen in Figures 17 to 22 inclusive.

Figure 17 represents, in perspective, a ver- 95 tical filing system, with the filing units in closed position.

Figure 18 represents a perspective view 100 similar to Figure 17 but showing one of the filing units in its open position.

Figure 19 represents a section on line 19— 19 of Figure 17.

Figure 20 represents a section on line 20— 105 20 of Figure 18 showing the manner in which the upward movement of a filing unit is limited.

Figure 21 represents a section on line 21— 110 21 of Figure 17.

Figure 22 represents, in perspective and in 115 detached position, one of the partition members employed.

Similar numerals of reference indicate corresponding parts.

Referring to the drawings.

Referring first to the embodiments seen in Figures 1 to 6 inclusive, 1 designates a cabinet the dimension of which may vary 5 widely in practice but which is provided with an open top which in proximity to its opposite marginal edges is provided with the laterally extending stop members 2 which are removable and secured in position by means of fastening devices 3 which are detachable in order that the stop members 2 which are in the form of rods or bars may be removed and thus permit the removal of any or all of the filing units 4. 10 Each filing unit is provided with a guide member 5, which, as illustrated, is in the form of a plate preferably of sheet metal having its bottom marginal edge laterally deflected to form a supporting flange 6 and 15 the side marginal edges are deflected, as at 7, in order to form the guide grooves 8. The plate is cut away at the upper corners, as at 9, and portions of the plate are deflected over, as indicated at 10, to close the 20 top of the grooves 8 and thus serve as stops for the ends 11 of a hinged rod 12 which latter consists of a rod extending substantially straight and then deflected upon itself to form guide portions 11, the free ends of 25 the rods being loosely anchored within the overturned flange 13 of the card-carrying frame 14 of the filing unit. The guide portions 11 are retained within the grooves 8 so that relative upward and downward 30 movement of the card-carrying frame 14 with respect to its guide plate is limited.

The marginal edge of the frame 14 opposite the overturned flange 13 is flanged over, as indicated at 15, in order to retain 40 the cards 16 in position. These cards may be connected with the frame in any desired manner so that they can be slidably mounted therein. One of the marginal edges 17 of the frame is also preferably deflected so 45 that when the cards are assembled they will lie beneath the frame. In this form of my invention when the frame of a filing unit is drawn upwardly by taking hold of its tab 18, the guide portions 11 will slide in the 50 groove 8 until limited by the stop flanges 10 and the frame will then when released drop into substantially a horizontal position, as seen in Figure 2, at which time all of the cards in the filing unit are readily accessible 55 and visible to the operator, whereas the upper edge of the guide plate 5 extends above the cabinet in a vertical position.

The stop flanges 10 are a desired distance below the top of the guide plate 5 so that 60 when the card-carrying frame 14 is again raised to its vertical position turning on the rod 12 as a fulcrum the upwardly extending portion of the guide member 5 will cause all of the cards carried by the frame to be 65 retained within the frame so that the frame

and its guide member will drop into its vertical position within the cabinet and the cards cannot protrude so as to be injured or to prevent such movement of a filing unit.

In the embodiment of my invention thus 70 described the cards when in filed position are retained in the frame in a sidewise position.

Referring now to the embodiment seen in Figures 7 to 15 inclusive, I have shown another form of my invention in which the filing unit is constructed in a different manner although the generic principle involved is the same, and in this embodiment I also illustrate a follower block although, as will 75 be apparent, no follower block is necessary in case the cabinet is filled with the filing units.

In this embodiment 19 illustrates the cabinet having an open top provided on opposite sides with the stop members 20 which are fixed if a follower block is employed.

21 designates the follower block which is 80 slideable beneath the stop members 20 and provided with a lateral extension 22 on which the card-carrying frame 23 of a filing unit 24 can rest when the frame is in its open position. The follower block is prevented from tilting by its engagement with the bottom of the box. Each filing unit 24 is provided with a guide member 25 in the 85 form of a plate having connected to it at opposite ends the vertically-extending spaced straps 26, the upper and lower ends of which are secured to the plate in any desired 90 manner.

These guide straps 26 at their upper ends terminate below the top of the guide member 25 which latter is recessed, as at 27. The card-carrying plate 23 has hinged to its bottom a bar 28 having the outwardly extending lugs 29 which extend into the spaces formed between the guide straps 26 and the 95 guide member 25, the straps 26, serving as guides for the lugs 29 and also to limit their upward and downward movement relatively to the guide member 25.

In this form of my invention, the operation is the same as that already described 100 except that the follower block is employed and its position adjusted when it is desired to insert or remove a complete filing unit from its cabinet.

Referring now to the embodiment seen in Figures 16 to 22 inclusive, I have shown 105 another form of my invention in which instead of having a card-carrying frame connected with its guide bar at one side it is connected at one end with its guide bar.

In this embodiment, it is simply necessary 110 to employ a partition or plate 30 which is cut away, as at 31, in order that it will be slideable in the cabinet 32 beneath the stop members 33 on opposite sides of the cabinet 115 near its upper edge. In this embodiment, 120

23^a designates a card-carrying frame which has hinged to one end a bar 34 having the outwardly extending lugs 35 which are stopped in their upward movement by contact with the stop members 33, which will be apparent.

In this embodiment, I may if desired, employ a follower block 36 having a lateral extension 37 on which a frame may rest 10 when in open position. Each frame is provided with a tab 38 which may receive any desired indexing tabulation. In this form of my invention when a card-carrying frame is raised and moved into its open position, 15 the cards are positioned longitudinally of the box instead of laterally as in the other embodiments described herein and necessarily must be normally in a standing-up position in the box.

20 It will now be apparent that I have devised a new and useful vertical filing system which embodies the features of advantage enumerated as desirable in the statement of the invention and the above description, and while I have, in the present instance, shown and described preferred embodiments thereof which will give in practice satisfactory and reliable results, it is to be understood that such embodiments are 25 susceptible of modification in various particulars without departing from the spirit or scope of the invention or sacrificing any of its advantages.

Having thus described my invention, 30 what I claim as new and desire to secure by Letters Patent, is:—

1. In a card filing system, a cabinet, card-carrying frames disposed vertically within said cabinet and adapted when raised to be 40 supported laterally above said cabinet to render the cards carried by said frames accessible, said frames having guide members which when in raised position extend above the cabinet.

45 2. In a card filing system, a cabinet, filing units disposed vertically within said cabinet and each consisting of a guide member and a card-carrying frame slidably connected with it and adapted to raise said guide member after the frame is raised to a predetermined extent, the card-carrying member being movable into a lateral position when raised to render the cards carried by it accessible.

55 3. In a card filing system, a cabinet, filing units disposed vertically within said cabinet and each consisting of a guide member and a card-carrying frame movably connected with it and adapted to raise said guide member when the frame is raised, the card-carrying member being movable into a lateral position when raised to render the cards carried by it accessible, said guide member serving to move the cards within the frame 60 when the frame is moved into the cabinet.

4. In a card filing system, a cabinet, filing units within said cabinet and each comprising a guide plate and a card-carrying frame slidably connected with it and adapted to raise said guide plate when the frame is 70 raised, said cabinet having means to limit the upward movement of said guide plate and said frame when raised being adapted to be moved into a lateral position to render all of its cards accessible. 75

5. In a card filing system, a cabinet having stop members on opposite sides, guide members adapted to engage said stop members when raised, card-carrying frames having limited vertical movement with respect 80 to said guide members and adapted when raised to be moved into a lateral position, said guide members serving to move protruding parts of the cards of a frame within such frame when the latter is moved into 85 vertical position within the cabinet.

6. In a card filing system, a filing unit adapted to be filed vertically and comprising a guide plate having guide flanges, a card-carrying frame, a member pivotally 90 connected therewith slidably connected with said guide plate and guided by said flanges, said plate having means to limit the upward movement of said pivoted member, and cards removably carried by said frame. 95

7. In a card filing system, a cabinet having removable stop members at opposite sides, filing units having guide members limited by said stop members and adapted to be filed vertically in the cabinet, each filing unit having a card-carrying frame guided by said guide members and adapted when raised to be moved in a lateral position to render its cards accessible. 100

8. In a card filing system, a cabinet, a card-carrying frame guided within said cabinet and adapted when raised vertically to be moved into a lateral position to expose its card, and a guide member for each frame adapted to prevent the protruding of its cards when such frame is moved into the cabinet. 105

9. In a card filing system, a cabinet, card-carrying frames filed vertically within the cabinet, a follower block for said frames, 115 said frames when raised being adapted to be moved into a lateral position to expose their cards and the follower block being adapted to support the frames in proximity thereto when so moved.

10. In a card filing system, a cabinet, card-carrying frames vertically disposed within said cabinet, a guide member for each frame connected thereto for limited relative movement with respect to its frame, to cause said guide member to be raised so as to project above the top of the cabinet when the frame is raised and to permit a frame when raised to assume a lateral position. 125

11. In a card filing system, a cabinet, card- 130

carrying units disposed in said cabinet and adapted to be pulled from the cabinet, said units comprising a card frame and a guide member to which the frame is articulately connected so as to be swung laterally thereon and expose the cards when the unit is pulled outwardly, said guide member when pulled outwardly extending beyond the articulated connection whereby when the frame ²⁰ is swung into position to enter the cabinet the outwardly extending portion of the guide member will press protruding parts to cards against the face of the frame and thus prevent injury to the cards during movement ²⁵ of the unit into the cabinet.

12. In a card filing system, a cabinet, card-carrying units slideable edgewise into

and out of said cabinet, each unit comprising a guide member and a card-supporting frame articulately connected to the member at points located inwardly from the adjacent edge, means for limiting movement of the member outwardly beyond an extent permitting lateral movement of the frame into a position to expose the cards, the portion of the member above the articulated connection serving to prevent protrusion of the cards when the frame is moved edgewise into the cabinet. ²⁰ ²⁵
